GAS RANGE PILOT HOOD

Edward J. Zarybnicky, Cleveland, Ohio, assignor, by
mesne assignments, to Aurora Corporation of Illinois,
a corporation of Illinois

Filed Dec. 22, 1960, Ser. No. 77,733
4 Claims. (Cl. 158—115)

This invention relates to gas range pilot light devices, and more particularly to improvements in draft and concussion shielding hood and baffle arrangements especially adapted for use in conjunction with the low B.t.u. type pilots such as the so-called hypodermic needle type lighter.

It is a primary object of the present invention to provide improved pilot port, housing, and draft baffle arrangements as aforesaid, whereby air breezes and shocks such as are caused for example by dropping a utensil onto the burner grate, will be successfully countered so that the pilot will not be extinguished.

Another object is to provide an improved device which is operable as aforesaid without impairment of its burner ignition capabilities.

Still another object is to provide an improved device as aforesaid which is designed to be relatively easily and inexpensively manufactured.

Other objects and advantages of the invention will be apparent from the following specification and accompanying drawings wherein:

FIG. 1 is a fragmentary sectional view through a range burner and a pilot light arrangement having one form of pilot housing and baffle of the invention mounted thereon;

FIG. 2 is an end view taken on line II—II of FIG. 1;

FIG. 3 is a section taken on line III—III of FIG. 1;

FIG. 4 is a section taken on line IV—IV of FIG. 1;

FIG. 5 is a plan view of the pilot housing and baffle device of FIG. 1; and

FIG. 6 is a fragmentary plan, on reduced scale, of a blanked metal sheet from which part of the device is fabricated.

As shown in FIG. 1, the range burner is indicated generally at 10 as having a main annular gas outlet chamber 12 and a charge port 14 for directing gas toward the pilot light device for burner ignition purposes. The burner cap is indicated at 15 and is provided with burner ports 16. The pilot supply tube is indicated at 18, and the jet 20 is of the "hypodermic needle" type supplying a minute flame 22 which normally burns as shown at all times.

As shown in FIGS. 1—5, a pilot housing of sheet metal form is provided to comprise a cylindrical wall portion 24 open at its front end and spanned at its lower rear end portion by a cross plate 26 which is centrally bored for a pressed fit upon the jet thimble carried by the supply tube 18, thereby mounting the housing to encompass the pilot flame as shown in FIG. 1. Adjacent its front end the housing 24 mounts interiorly thereof a baffle device designated generally at 30. This baffle may conveniently comprise a sheet metal stamping of conical cup-shaped form, press-fitted or otherwise mounted within the housing wall 24 as will be explained hereinafter.

As shown in FIGS. 1, 3, a combustion air inlet opening 32 of arcuate shape is provided through the upper rear end portion of the housing 24, and a similarly shaped opening 34 is provided through the baffle device 30, as shown in FIGS. 1, 2, 3. A pair of vent holes 36—36 are also provided in the central ceiling portion of the housing 24, and the lower front end portion of the housing is cut away as indicated at 38 (FIGS. 1, 4) to supply primary air to the pilot flame.

The housing member 24 may be either fabricated of a

plurality of pieces welded or otherwise fixed together; or it may be conveniently formed of a single piece of sheet metal initially stamped as shown in FIG. 6 to provide the openings referred to hereinabove and then rolled into the form of the housing structure as shown in FIGS. 1—5. Thus the back wall portion 26, having arms 40—40 integrating the back wall 26 with the main body portions 24—24 will be suitably punched as indicated at 41 to receive the hub portion 42 of the jet piece 20 in press-fitted relation therein. The reduced diameter shank portion 44 of the jet piece then receives the gas supply tube 18 in press-fitted relation thereon, to complete the rear end assembly of the device.

For mounting the baffle 30 interiorly of the housing as shown in FIGS. 1, 4, the opposite side wall portions of the housing 24 are notched as indicated at 46—46 and the baffle disc is provided at its opposite sides with laterally extending arms 48—48 so shaped as to slide-fit into the notches 46—46 of the housing. The outer ends 49 of the fingers 48 are then adapted to be bent progressively inwardly against the outside walls of the housing until the extreme finger end portions 49 lock into slots 50—50 previously punched through the opposite side walls of the housing 24.

In operation, when the burner control valve is turned to an open position gas is supplied simultaneously to the main burner ports 16 and to the charge port 14, and the gas from the charge port is directed into the hood through the opening 34 where it becomes ignited by the pilot flame 22 and flashes back to burn at the charge port. This causes ignition of the gas at the main burner. Thus, the device operates to allow instant ignition of the burner, while at all times the hood and baffle protect the pilot flame 22 against extinguishment from drafts or concussion effects, or the like. The opening 32 at the top rear portion of the hood is provided to vent the combustion products of both the pilot supply and the charge port gas. The openings 36—36 in the ceiling of the hood also operate to vent off pilot light combustion products, but also function as peep holes through which operation of the pilot light may be conveniently observed.

Although in the drawing herewith the baffle member 30 is shown to be of concave or conical form, in lieu thereof it may be of flat form or even convexly conical. The thimble 44 is also provided with a trap extension 54, and the arrangement of the fuel supply line 18 and the extension 54 of the jet piece as shown in FIGS. 1 and 5, provides a dust and dirt trap in the fuel supply to the pilot light. It will of course be appreciated that whereas only one form of the invention has been illustrated and described in detail herein various changes may be made therein without departing from the spirit of the invention or the scope of the accompanying claims.

I claim:

1. In combination, a gas burner and a pilot light housing device comprising a generally cylindrically shaped hood having a rear end partial closure plate, said closure plate being centrally bored, a pilot light jet member extending through the bore in said closure plate, a draft baffle device disposed transversely of the interior of said hood adjacent the front end thereof, said baffle being of concave conical form and provided with a gas inlet aperture adjacent the upper marginal edge thereof, said burner having main burner ports and a charge port directed laterally therefrom towards said baffle below said gas inlet aperture, said hood having a portion overhanging said baffle on that side thereof facing said charge port, and means including said charge port, said overhanging portion of the hood and said gas inlet aperture to direct gas from the charge port to said jet member.
2. In combination, a gas burner and a pilot light housing device comprising a hood having a mounting mem-

ber at its rear end, said mounting member having an opening, a pilot light jet member projecting through said opening, a draft baffle device disposed transversely of the interior of said hood intermediately of its ends, said baffle being of transverse wall form and provided with a gas transfer aperture adjacent the ceiling thereof, said burner having main burner ports and a charge port directed laterally therefrom towards said baffle below said gas transfer aperture, said hood having a portion overhanging said baffle on that side thereof facing said charge port, and means including said charge port, said overhanging portion of the hood and said gas transfer aperture to direct gas from the charge port to said jet member.

3. In combination, a gas burner and a pilot light housing device comprising a generally cylindrically shaped hood having a closure plate at its rear end apertured at the top thereof, a pilot light jet member mounted on said closure plate, said hood being cut away at a bottom cylindrical wall portion thereof and having gas outlet and peep hole apertures in the top wall portion thereof, a draft baffle device disposed transversely of the interior of said hood intermediately of its ends, said baffle comprising a transverse wall provided with a gas transfer aperture adjacent the upper marginal edge thereof, said burner having a charge port directed laterally therefrom towards said baffle below said gas inlet aperture, said hood having

5 a portion overhanging said baffle on that side thereof facing said charge port, and means including said charge port, said overhanging portion of the hood and said gas transfer aperture to direct gas from the charge port to said jet member.

10 4. In combination, a gas burner and a pilot light housing device comprising a cylindrically shaped hood having a partial closure at its rear end and being partially open at its front bottom wall portion, a pilot light jet burning within said hood, a draft baffle device disposed transversely of the interior of said hood adjacent the front end thereof, said baffle being provided with a gas inlet aperture adjacent the ceiling of said hood, said burner having 15 main burner ports and a charge port directed laterally therefrom, said hood having a portion overhanging said baffle on that side thereof facing said charge port, and means including said charge port, said overhanging portion of the hood and said gas inlet aperture to direct gas 20 from the charge port to said jet member.
